PILGERING ROLLING MILL

Application filed February 16, 1931, Serial No. 516,161, and in Germany May 26, 1930.

The purpose of recent research has been to discover new processes for the manufacture of seamless tubes with extremely thin walls, so as to make them better able to compete with welded tubes.

The disadvantage of the pilgering method—which is the method exclusively adopted in Germany for the production of large seamless tubes—is that owing to the calibration hitherto employed it is not possible to reduce the usual thickness of the walls of the tubes below the so-called normal thickness. This normal thickness and therefore the weight per metre of the tubes is so great that the seamless tubes are in certain cases inferior from a commercial point of view to welded tubes which can be produced with extremely thin walls.

The reason why it has not heretofore been possible to produce a tube with thinner walls than the normal thickness by means of the known pilgering rolling mill calibration employed, is that in the form of pass hitherto used the stretching operation is effected almost entirely by the bottom of the pass in the "mouth" of the roll, whereas those parts of the pass extending to the sides of the pass contribute to the shaping only to a slight extent.

Whereas the material being rolled is scarcely stretched at all at the sides of the pass, it has a very pronounced tendency at the bottom of the pass to flow in the longitudinal direction of the hollow body under high locally concentrated rolling pressure. The effect is to distort the material very considerably so that when the thickness of the walls is reduced below the normal, bursting and over-rolling occur at the bottom of the pass.

The invention is diagrammatically illustrated in the accompanying drawing.

Fig. 1 is a fragmentary detail section taken radially through one of the rolls shown in Fig. 2.

Fig. 2 is a longitudinal section through the bottom of a pilgering roll.

Fig. 3 is a fragmentary cross section through the pass parallel to the plane in which the axes of the rolls lie during the working operation.

The fact that in the known types of pass it is chiefly the bottom of the pass that operates in the "mouth" of the rolls, is clear from the fact that the cross sections in which the material is chiefly simultaneously rolled are ellipses or flat ovals, the major axes of which lie in the gap between the rolls parallel to the axis of the rolls. The material to be rolled is in the known pilger rolls as well as in that according to the invention shaped during treatment by the "mouth" of the pass in cross-sections which lie at a certain distance parallel with the line joining the centres of the rolls, because the shortest distance, from roll surface to roll surface does not lie in the centre line but at a distance therefrom. As heretofore all the passes were so formed in the roll that in radial section through the roll, for example in the radial section O_1O_2 (Fig. 2), the known passes have a semi-circular form with lateral bevelled parts or even flat ovals having the minor axis perpendicular to the axis of the roll, it follows that a section, which is taken parallel to the line joining the centres O_1 and O_2 of the rolls at a definite distance, for example the section A_1A_2 (Fig. 2) lying at the distance a from the line O_1O_2 is of flat elliptical or oval form that is quite inappreciable because half of the width of the pass at $2'$ is greater than the length A_1A_2' representing the depth of the pass in the cross-section A_1A_2 . In other words, the distance between the roll and the circular mandrel is at the bottom of the pass considerably less than at the sides of the pass. The effect is that the roll, the material being rolled, and the mandrel are locally overstrained which makes it impossible to roll walls below the normal thickness.

Furthermore, passes are known which, in radial section through the roll, are elliptical or of any flat-oval shape, such that the major axis of the ellipse lies parallel with the axis of the roll, and that therefore the pass is not so deep as it is wide. Such formation of the pass has, as will be understood, defects inherent in passes of circular radial cross-section hereinbefore described, but to an increased degree, because the distance from roll to mandrel in the cross-sections in which the

main rolling operation takes place is considerably less at the bottom of the pass than at the sides. Such passes thus stretch the material being rolled in a still more irregular manner than passes which are circular in radial section and stress the material being rolled still more.

The object of the invention is so to form the pass that the pressure of the roll is distributed over the whole width of the pass, points of rolling pressure at the bottom of the pass are avoided, and the material being rolled is stretched as uniformly as possible over its whole periphery. According to the invention the distances from the pass to the mandrel in the cross-sections $A_1 A_2$ (Fig. 2) in which the principal work of rolling is carried out, are the same—in other words the shape of the pass in this cross-section is a circle with the diameter $\phi = A_1 A_2$ (Fig. 3) and thus the material to be rolled is uniformly stretched. In order to obtain such a circular shape in the cross-section of the principal work of rolling, the pass of the pilgering "mouth" in radial section through the roll according to the invention is given such an elliptical or other oval shape that the major axis of the ellipse is perpendicular to the axis of the roll, the minor axis being parallel to it. Then the desired circle can be obtained due to the fact that the length $A_1 A_2'$ (Fig. 2) is shorter than the depth of the pass in the radial section $O_1 O_2'$ to which the point $2'$ is belonging. The ellipticity of the ellipse (the major axis of which is perpendicular to the axis of the roll) decreases then gradually from the beginning of the pilgering "mouth" to the beginning of the polishing surface and the ellipse changes to a circle at the point of transition into the polishing pass.

In Figure 2, W denotes the roll, H the hol-

low body, D the mandrel and the curve I the mouth, the arc II the polishing surface, and the curve III the outlet from the pass.

One condition of the invention is that the cross-section which at $A_1 A_2$ in Figure 2 is parallel to the line joining the centres $O_1 O_2$ and is shown in Figure 3, is circular without counting the lateral pass openings. This results from the elliptical formation of the pass in cross-section through the roll (for example $O_1 O_2'$ in Figure 2) so that half the major axis a of the ellipse is equal to $A_1 A_2'$ in Figures 1 and 2 and the minor axis $2b$ of the ellipse is equal to $B B'$.

As the cross-section $A_1 A_2$, in which the material being rolled is chiefly worked, moves gradually to the centre of the roll frame as the roll rotates and the mouth of the pass rolls over the material, the ellipticity of the ellipse decreases from the first engagement by the mouth up to the transition into the polishing pass until the radial section through the roll in the polishing pass is circular.

I claim:

A roll pass for pilgering rolling mills, characterized in that the pass at the "mouth" of the pilger is given such an elliptical shape in radial section through the roll that the pass of the roll is circular in the cross-section which is perpendicular to the axis of the work at the point where the principal rolling operation is carried out by the pass, the ellipticity of the ellipse, the major axis of which is perpendicular to the axis of the roll, decreasing continuously from the beginning of the pilgering mouth to the beginning of the polishing surface and the ellipse changing to circular shape on the transition into the polishing pass.
